(57) **CLAIM**

The ornamental design for a fluid applicator, as shown and described.

DESCRIPTION

FIG. 1 is a perspective view of a fluid applicator according to the present invention;

FIG. 2 is a cross section of FIG. 1 along the line 2-2;

FIG. 3 is a right side elevation view of FIG. 1;

FIG. 4 is a left side elevation view of FIG. 1;

FIG. 5 is a top plan view of FIG. 1;

FIG. 6 is a bottom plan view of FIG. 1;

FIG. 7 is a front elevation view of FIG. 1; and,

FIG. 8 is a rear elevation view of FIG. 1.

Fluid applicator is shown with a symbolic break in its length. The appearance of any portion of the article between the break lines forms no part of the design. The broken lines represent the boundaries of the claim and form no part of the claim.
